UNITED STATES PATENT OFFICE.

WILLIAM EDGAR MUNTZ, OF LONDON, ENGLAND.

MEANS FOR REGULATING THE FLOW OF LIQUIDS.

Application filed March 2, 1921. Serial No. 449,138.

(GRANTED UNDER THE PROVISIONS OF THE ACT OF MARCH 3, 1921, 41 STAT. L., 1313.)

To all whom it may concern:

Be it known that I, WILLIAM EDGAR MUNTZ, a subject of the King of Great Britain, and resident of 24 Southampton Buildings, London, England, have invented new and useful Improvements in Means for Regulating the Flow of Liquids, of which the following is a specification.

This invention relates to improvements in the regulation of the flow of fluids.

The object of this invention is to provide means whereby a number of different volumes of a mixture of two fluids can be discharged, whilst at the same time the proportion of the two fluids for each volume is capable of infinite variation.

In one way of carrying out my invention as applied to a spigot tap, the two fluids in the casing are separated by a diaphragm in the casing situated in a plane at right angles to the axis of rotation of the spigot plug. In the surface of the casing contiguous to the plug I cut one or more pairs of triangular, rectangular or trapezoidal slots, the longitudinal centre lines of the triangular slots being preferably at right angles to the axis of rotation, one slot above and the other below the diaphragm dividing the two fluids, such triangular slots facing opposite ways.

In the spigot I form along practically its full length a slot, preferably oblong, whose longitudinal centre line is preferably parallel to the axis of the spigot. The base of each casing slot is of such width that when it inter-registers with the slot in the spigot plug a certain predetermined fluid passage results, say $\frac{1}{4}$, $\frac{1}{2}$ or $\frac{3}{4}$ or all of the fuel supply.

The pairs of triangular casing slots face opposite ways and the base of one so far overhangs the apex of the other and vice versa that when the spigot slot registers with the extremity of the base of one of the two casing slots (in that particular sector) to give the predetermined fluid passage above alluded to, the apex of the other slot does not impinge and is just clear of the said spigot slot so as to release the full quantity of one fluid (undiluted by the other), for which that particular sector is designed.

When applying my invention to a spigot tap in which two fluids in the casing are separated by a diaphragm in the casing in a plane parallel to the axis of rotation of

the spigot plug I form two slots in the plug diametrically opposite to each other, one slot extending from the top near to the middle of the plug, whilst the other slot extends from the bottom near to the middle of the plug. In this case the arrangement of the slots in the casing is similar, each slot in the plug being adapted to uncover slots governing the flow of one fluid during one half revolution of the plug and slots governing the flow of the other fluid during the other half revolution of the spigot.

From the above it will be understood that as the spigot slot is moved the volume of the fluid discharge remains practically constant until the full volume of one of the fluids is being discharged, whilst the proportion of the two ingredients is capable of infinite variation.

Whilst the invention as above described is particularly useful for water taps as used for certain purposes, it is also useful for incandescent gas burners, gas fires and the like, as it gives positive air admission which is so desirable, and also enables the proportion of air to gas to be varied at any moment as the pressure and quality of either or both gas and atmospheric air may change.

In the above invention I can not only provide for one actuating handle to govern the variations in cross sectional areas up to the full available supply of both fluids combined, but also for the hermetic sealing of the outlets of both fluids.

My invention is illustrated in the accompanying drawings, in which Figure 1 shows the development or layout of a casing of a spigot tap having a diaphragm in a plane at right angles to the axis of the plug and suitable for regulating the flow of hot and cold water, and Figure 2 shows a similar layout in which the casing has a diaphragm parallel with the axis of rotation of the plug. Figure 3 is a sectional elevation of a tap and Figure 4 is an end elevation of Figure 3.

For convenience in describing the invention the casing has been divided by dotted lines into equal parts numbered 0, 10, 20 etc.

Referring more particularly to Figure 1, A is a diaphragm dividing the casing, cold water, for example being admitted to the casing above, and hot water below, the dia-

phragm. The slots in the casing are represented by the shaded portions B, C, D, E, F. The full lines G represent the slot in the spigot. When the slot G coincides with the part 0—10, $\frac{1}{2}$ of the full supply of cold water will be discharged; as the slot G is moved to the right the supply of cold water is gradually decreased and an increasing supply of hot water allowed until the slot coincides with the part 50—60, in which case $\frac{1}{2}$ of the total supply of hot water will be discharged, the supply of cold water being entirely cut off. When the slot G is in any position coinciding with the part 0—60 of the casing the total flow of water through the tap will be $\frac{1}{2}$ of the full supply. When the slot G coincides with the part 60—70, $\frac{1}{2}$ the full supply of hot water will be discharged; as the slot G is moved to the right the supply of hot water is decreased and an increasing supply of cold water allowed until the slot coincides with the part 110—120, in which case $\frac{1}{2}$ of the total supply of cold water will be discharged, the supply of hot water being entirely cut off. When the slot G is in any position coinciding with the part 60—120 of the casing the total flow of water through the tap will be $\frac{1}{2}$ of the full supply. Similarly when the slot is moved from the part 120—130 or 170—180, $\frac{1}{2}$ of the supply of cold water will at first flow, this will be increasingly diluted with hot water, the cold water being cut off until at 170—180 the supply of cold water will be cut off and $\frac{1}{2}$ of the supply of hot water will flow. When the slot G coincides with the part 180—190 the full supply of hot water will flow, this will gradually be diluted with cold water as the slot G is moved to the right until the position 230—240 is reached, when the full supply of both hot and cold water will flow. The supply of hot water will then be gradually decreased until in the position 280—290 the hot water is entirely shut off and the full supply of cold water flows. When the slot G coincides with the part 290—305 the hot and cold water are entirely shut off.

50 In the arrangement shown in Figure 2 there are two slots G in the spigot each slot extending slightly less than half the length of the spigot. During one half of the revolution of the spigot each slot controls the flow of one fluid and during the other half revolution of the spigot controls the flow of the other fluid. There are also two diaphragms A.

60 Referring now to Figures 3 and 4 which show a tap made in conformity with my invention as illustrated in Figure 2, H represents the housing of a tap to which two fluids are admitted by inlet pipes J, K. The bottom of the housing is provided with an inturned flange L. M is a truncated cone

shaped casing having tapered flanges N, O, and two webs or diaphragms P which divide the housing H into two fluid containers arranged diametrically opposite each other. The flanges N, O, and ribs P are ground into the housing H so as to form a fluid tight joint, the cone casing M being secured in position by screws S. T is a hollow spigot plug which is ground into the cone casing M and is held to its seating with uniform pressure by means of a spring U and is actuated by a handle V and spindle W provided with projections X which engage recesses in the plug T. In the cone casing M and plug T are cut slots corresponding to those shown in Figure 2, but to a smaller scale. Fluid entering the inlet pipes J, K, passes through the slots into the plug T and thence to a sump Y communicating with a spout Z.

What I claim is:—

1. A device to control the mixing of fluids which, when allowing to pass different predetermined fractions only of the total possible combined volumes of flow of the fluids, permits of infinite variations in the proportions of the components of such predetermined fractions of the total of the possible volume through the device.

2. A device of the character described comprising, a hollow spigot plug, a casing into which said plug is fitted, said plug and casing being differentially perforate, means for permitting the inflow of fluids of different character to different portions of the circumference of said casing, and means for rotating the plug in the casing to bring the perforate portions of the plug and casing into different relative positions of register with respect to each other, whereby the total volume of the combined fluids of different character passing through said device as well as the proportions of said fluids to each other in said combined volume may be varied and predetermined.

3. A device of the character described comprising, a hollow spigot plug, a casing into which said plug is fitted, said plug having a pair of slots in its wall extending in a direction substantially parallel to its axis of rotation and throughout a part of its length, said casing being provided with a plurality of pairs of slots extending in a direction substantially at right angles to the axis of rotation of the plug, each of said slots having a substantially triangular portion and the triangular portions of each slot of a pair tapering in opposite directions, means for rotating the spigot plug in the casing for causing the spigot slots and casing slots to inter-register in different relationships, a housing surrounding said casing with a water-tight fit, opposed webs or diaphragms extending substantially parallel to the axis of rotation of the spigot plug and

connecting the casing and housing for dividing the latter into two water-tight compartments, and means for permitting the inflow of fluids of different character to the 5 said compartments of the housing.

4. A device of the character described comprising, a hollow spigot plug, a casing into which said plug is fitted, said plug having a pair of slots in its wall extending in a 10 direction substantially parallel to its axis of rotation and throughout a part of its length, said casing being provided with a plurality of pairs of slots extending in a direction substantially at right angles to the axis of 15 rotation of the plug, each of said slots having a base portion equivalent in area to a predetermined fraction of the area of the slot in the spigot plug and a substantially triangular portion, the triangular portions 20 of each slot of a pair tapering in opposite directions, means for rotating the spigot plug in the casing for causing the spigot slots and casing slots to inter-register in different relationships, a housing surrounding 25 said casing with a water-tight fit, opposed webs or diaphragms extending substantially parallel to the axis of rotation of the spigot plug and connecting the casing and housing for dividing the latter into two water-tight 30 compartments, and means for permitting the inflow of fluids of different character to the 35 said compartments of the housing.

5. A device of the character described comprising, a hollow spigot plug, a casing into which said plug is fitted, said plug having a pair of slots in its wall substantially 40 parallel to its axis of rotation, one of said slots lying above and the other below the horizontal central plane of the plug, said 45 casing being provided with a plurality of pairs of slots extending in a direction substantially at right angles to the axis of rotation of the plug, each of said slots having a substantially triangular portion, a housing 50 surrounding said casing with a water-tight fit, opposed webs or diaphragms extending substantially parallel to the axis of rotation of the spigot plug and connecting the casing and housing for dividing the latter into two 55 water-tight compartments, the said triangular portions of the slots in the casing tapering oppositely to each other on each side of the said webs, means for permitting the inflow of fluids of different character to the 60 said compartments of the housing, and

means for rotating the spigot plug in the casing for causing the slots in the spigot plug to inter-register either simultaneously or individually with the casing slots in different relationships. 65

6. A device of the character described comprising, a hollow spigot plug, a casing into which said plug is fitted, said plug having a pair of slots in its wall substantially parallel to its axis of rotation, one of said 70 slots lying above and the other below the horizontal central plane of the plug, said casing being provided with a plurality of pairs of slots extending in a direction substantially at right angles to the axis of rotation of the plug, each of said slots having a substantially triangular portion, certain of said slots having a portion equivalent in area to a predetermined fraction of the area of the slots in the spigot plug, a housing 75 surrounding said casing with a water-tight fit, opposed webs or diaphragms extending substantially parallel to the axis of rotation of the spigot plug and connecting the casing and housing for dividing the latter into two 80 water-tight compartments, the said triangular portions of the slots in the casing tapering oppositely to each other on each side of the said webs, means for permitting the inflow of fluids of different character to the 85 said compartments of the housing, and means for rotating the spigot plug in the casing for causing the slots in the spigot plug to inter-register either simultaneously or individually with the casing slots in different relationships. 90

7. In a valve device, a housing, a pair of inlet ports in the housing for different sources of supply, a valve within the housing, a pair of ports in the valve, each port of one pair of ports comprising a full width portion and a tapered portion, and arranged to be so brought into registration with a corresponding port of the other pair of ports, that when the full width portion of either port of the said one pair of ports is beginning to leave registry with its corresponding inlet port, the other of the said one pair of ports is beginning to make registry with its corresponding port. 100

In testimony that I claim the foregoing as my invention I have signed my name this 11th day of February, 1921.

, WILLIAM EDGAR MUNTZ.
